HEAD VALVE FOR PRESSES

Fletcher Schaum, Philadelphia, Pa., assignor to
 Fletcher Works, Philadelphia, Pa., a corpora-
 tion of Pennsylvania

Application January 27, 1939, Serial No. 253,218

1 Claim. (Cl. 251—31)

My invention relates to new and useful improvements in valves, and more particularly to what is known as a head valve for use in steam presses.

In the present instance, the steam press is used for pressing clothes, which, as is well known, consists of a pivotal head in which there is a live steam chamber, so that when the garment is placed on the buck and the head forced 10 downwardly on the buck, the steam is liberated by a head valve and then drawn by a vacuum through the garment and buck. The head valve, therefore, is subjected to long and hard usage and it is highly desirable to provide a valve that 15 will withstand this constant usage and, at the same time, call for little or no packing or repair.

One of the objects of the present invention is to produce a head valve of the packless type, so that the steam is prevented from reaching the 20 piston rod and the necessity of a packing joint or box for said rod is entirely eliminated.

A further object of the invention is to provide a rugged head valve that may be quickly inserted within the head of the press and held in 25 place by a simple lock nut, there being provided within the valve body a piston and so-called piston rod, the latter being enclosed within an expandible copper corrugated bellows, so that regardless of the amount of wear that the valve 30 is subjected to, there is no likelihood of steam escaping around the piston rod.

Still another object of the invention is to provide a head valve that is simple and efficient in action, presents no mechanical difficulties in 35 its manufacture, and calls for but little machine work.

With these and other objects in view, the invention consists in certain new and novel features and combination of parts, as will be hereinafter more fully explained and pointed out in 40 the claim.

Referring now to the drawing showing a preferred embodiment,

Fig. 1 is a fragmentary sectional view showing a part of the live steam chamber of the head of a press and showing the head valve in its open position, the dot-and-dash lines showing the position of the handle when the valve is closed;

Fig. 2 is a sectional view showing the head valve with the piston rod removed and showing the direction of the steam through the valve, the section being taken at right angles to Fig. 1;

Fig. 3 is a transverse sectional view taken on 55 the line 3—3 of Fig. 2;

Fig. 4 is a sectional view taken on the line 4—4 of Fig. 2; and

Fig. 5 is a sectional view taken on the line 5—5 of Fig. 2.

Referring now more in detail to the several 5 views, and for the moment to Fig. 1, there is shown a fragmentary portion of the head 1 of a steam clothes press, in which there may be seen the live steam chamber 2 and likewise the chamber 3, into which the steam is to be admitted, so that it may pass through perforations 4 in the under surface of the head and then through a padding 5 and its sheet or cover 6, where it will then be drawn through the garment (not shown) into the buck (not shown). 10 A baffle plate 7 is provided within the chamber 3, so that the steam on entering the chamber 3 will be deflected horizontally along the chamber before passing through the various openings 4.

The head 1 of the press is provided with the 20 dome-shaped portion 8, centrally of which is the plane opening 9 to receive the head valve, shortly to be described, and likewise in the lower wall 10 of the live steam chamber, there is the threaded opening 11, into which is screwed the lower 25 end of the head valve.

Referring now to the invention, that is, the valve per se, the body portion consists preferably of a cast brass body 12, which is externally threaded at its lower end, as at 13; likewise threaded near its upper end, as at 14; and internally threaded at its upper end, as at 15. Vertical passageways 16 may be seen formed on opposite sides of the center, which, in turn, merge with the slightly smaller passageways 17, 30 while extending transversely of the central portion 18 of the valve are the ports or inlet openings 19, which connect with the small central bore 20, which is open at its top, as at 21.

The upper portion of the body 12 (Fig. 2) is 40 provided with the large central bore or cylinder 22, in which travels the piston 23, in the under surface of which is the fiber disk 24, which is to seat on the upper end of the central portion 18 to thus open or close the valve and permit the 45 steam to pass down the passageways 17 and 16 into the chamber 3 of the head of the press.

The piston 23 is also centrally bored, as at 25, to receive a base or nut 26 (Fig. 1), in which is threaded the rod 27, which latter extends 50 through the head sleeve 28. Extending between the head sleeve 28 and the nut 26 is the corrugated copper bellows 29, which is capable of expansion and contraction and forms a seal-tight joint between the nut 26 and the head 55

sleeve 28, so that steam can never pass about the rod 27 and leak out around the rod 27 where it passes through the head sleeve 28. This bellows type of packing is a conventional one.

- 5 To lock the valve in place, there is shown the lock nut 30, which may bear against a washer 31, as seen in Fig. 1, so that no steam can escape from the live steam chamber about the receptive opening of the valve. There is also shown an 10 integral nut 32 on the body of the valve just above the threaded portion 14 for conveniently inserting or removing the valve in the head. About the top of the body portion of the valve, that is, at the zone of the internal threads 15, 15 may be seen a collar 33 with its hook 34 for the receptive end of a spring 35, which spring is also fastened at its opposite end to the bolt 36, on which fits the nut 37. Thus, the tension on the spring may at all times be regulated by the manipulation of the nut. The bolt 36 passes through the outer end of the handle 38, which is pivoted, as at 39, to a bracket 33^a, while from this handle extends the aforementioned rod 27, which is connected to the handle by the clevis 25 and pin 40. Also, stop means are provided for limiting the downward movement of the handle, as may be seen from Fig. 1.

Threaded within the upper end of the body 12 is the head 41, which is provided with the 30 threaded cap 42, which, in turn, is drawn down tightly over the aforementioned sleeve 28, while through the sleeve and cap, of course, extends the aforementioned piston rod 27. It will be noticed that the spring 35 will normally pull the outer end of the handle downwardly and likewise normally hold the piston 23 on its seat, so that the live steam, although entering the passageway or bore 20, cannot escape into the ports 17 and 16 until the piston is elevated or opened. However, on a downward pressure by the operator on the handle 38, the piston, 40 through the piston rod, will be elevated and removed from its seat, as shown in Figs. 1 and 2, thus permitting the steam to pass from the bore 45 20 into the passageways 17 and 16 down to the

chamber 3 and out through the aforementioned perforations 4.

From the foregoing, it will be seen that there is no possibility of the steam leaking past the only movable part, the piston rod (exclusive of the piston), as the corrugated bellows prevents the steam from reaching the piston rod, and regardless of how much the opening in the sleeve 28 wears or regardless of how much the piston rod wears, the operation of the valve will in no 10 way be affected.

If the washer 31 ever wears, the lock nut may be quickly loosened and the valve removed and a new washer placed in position. Also, as heretofore mentioned, the body of the valve is one that 15 may be readily cast while the machine work for the piston and central parts of the valve has been reduced to a minimum.

I have found that a valve of this type will give efficient and continual service without necessi- 20 tating any repairs.

Finally, by simply unscrewing the head, it is the matter of a moment to slip out the piston and renew the valve disk when the same becomes worn.

Having thus described my invention, what I claim as new and desire to secure by Letters Patent is:

A head valve including a body, said body having inlet and outlet ports, a piston for opening 30 and closing the ports, said piston having a centrally located chamber in its upper portion, a piston rod within the valve body, a head on said valve body through which said piston rod also operates, a sleeve in said head and a steam-tight 35 bellows enclosing said piston rod and fitting within said sleeve, a member secured to the bottom of the piston rod and fitting within the chamber in said piston and the bellows also fitting within said member so that the piston rod 40 is entirely enclosed to thus prevent the steam from reaching the same, and a cap on said head and pressing on said sleeve to thereby hold the same in a seal-tight condition.
